Andrew Sonafelt Inventor

By *Clarence O'Brien*, Attorney

UNITED STATES PATENT OFFICE

ANDREW SONAFELT, OF ENID, OKLAHOMA

WINDOW SCREEN

Application filed February 12, 1930. Serial No. 427,778.

This invention relates to window screens and more particularly to devices of this character of the all metal type and has for one of its objects to provide, in a manner as hereinafter set forth, a window screen of this character which is adapted to be expeditiously mounted in a window frame in a manner to permit same to swing in a horizontal plane to facilitate washing of the outside of the windows or for any other purpose.

Another important object of the invention is to provide a window screen of the character set forth which embodies novel means for securely mounting the screen on the supporting frame therefor.

Other objects of the invention are to provide a window screen which will be simple in construction, strong, durable, efficient in use and which may be manufactured at low cost.

All of the foregoing and still further objects and advantages of the invention will become apparent from a study of the following specification, taken in connection with the accompanying drawings wherein like characters of reference designate corresponding parts throughout the several views and wherein:

Figure 1 is a view of a full size screen which covers an entire window opening,

Figure 2 is a view in front elevation showing a half size screen which covers only the lower portion of a window opening,

Figure 3 is a fragmentary view in front elevation on an enlarged scale showing a corner portion of the window screen,

Figure 4 is a fragmentary horizontal cross sectional view taken substantially on the line 4-4 of Figure 1, looking downwardly,

Figure 5 is a fragmentary horizontal sectional view taken substantially on the line 5-5 of Figure 1 and looking downwardly,

Figure 6 is a horizontal sectional view taken substantially on the line 6-6 of Figure 3,

Figure 7 is a sectional view taken substantially on the line 7-7 of Figure 3,

Figure 8 is a detail view in front elevation of one of the angular corner reinforcing caps,

Figure 9 is a view in horizontal section taken through the window frame and show-

ing, in full lines, the window screen secured in closed position and in dotted lines showing said screen swung to open position.

Referring to the drawing in detail, the reference character 1 designates generally the window frame which includes the vertical side members 2 and 3, the sill 4, the upper cross member 5 and the guide strips 6 and 7 secured on the inner sides of the vertical members 2 and 3 respectively in spaced relation to the outer faces thereof.

All of the foregoing is of the usual window construction and forms no part of this invention. The window screen constituting this invention comprises a rectangular metallic frame designated generally by the reference numeral 8 and comprising the vertical side members 9 and 10, a lower cross member or end bar 11 and an upper cross member or end bar 12. The members 9 to 12 inclusive of the frame are stamped from flat strips of metal in a manner to provide an intermediate substantially V-shaped longitudinally extending projection 13 and the inner marginal portion of said members are folded back upon themselves as indicated at 14.

The outer marginal portions of the members 9 to 12 inclusive are rolled back to provide a comparatively large loop 15 which extends entirely around the outer marginal portion of the frame.

As illustrated to advantage in Figure 6 of the drawing, the marginal portions of the screen 16 extend in overlapping relation to the members 9 to 12 inclusive of the frame 8 and terminate adjacent the outer longitudinal extremities of the V-shaped projection 13. Elongated clamping plates or strips 17 of substantially V-shaped cross section and formed preferably of metal are mounted on the V-shaped projection 13 with the marginal portion of the screen 16 clamped therebetween and said clamping strips are secured in position through the medium of struck out tongues or prongs 18 which are bent outwardly from the members 9 to 12 inclusive on opposite sides of the projections 13 and are bent inwardly toward each other in a manner to extend over the longitudinal marginal portion of the clamping strips 17.

Still referring to Figure 6, it will be seen that the tongues or prongs 18 disposed on the inner sides of the clamping strip 17 penetrates the screen 16 and constitutes positive anchoring means therefor.

As best illustrated in Figures 1 and 4 of the drawing, the vertical side members 9 of the screen frame 8 is provided adjacent its upper and lower ends and at a point adjacent to where said side member merges into the loop portion 15 when slots or openings 19 for the passage of the loop portion 20 of a supporting hinge member 21 which is secured, as at 22 to the vertical side members 3 of the window frame 1.

The loop 20 of the hinge member 21 encircles the loop portion 15 of the side member 9 of the frame in a manner to support said frame within the window frame 1 to permit swinging movement thereof in a horizontal plane as indicated in dotted lines in Figure 9 of the drawings.

Referring to Figure 5 of the drawings, it will be seen that the vertical side member 10 of the screen frame 8 has anchored thereto a swingable hook 23 adapted for engagement with an eye bolt 24 mounted in the guide strip 6 for securing the screen in closed position.

Angular metallic corner reinforcing caps 25, see Figures 3 and 8, are mounted on the corner portions of the screen frame 8 on one side to lend rigidity to said frame and strengthen the joint between the members 9 to 12 inclusive thereof. The caps 25 are provided with rolled outer marginal portions 26 adapted to extend over the adjacent loop portion 15, as clearly seen in Figure 3. Angular corner plates A are mounted on the corner portions of the frame on the opposite side from the caps 25 to further strengthen same and said plates extend into the loops 15.

As seen in Figure 4 the construction of the hinge members 21 is such that the screen is supported within the window frame 1 and the outer sides of the loop portion 15 are substantially flush with the outer sides of said window frame 1.

It is believed that the many advantages of a window screen constructed in accordance with this invention will be readily understood and although the preferred embodiment of the invention is as illustrated and described, it is to be understood that changes in the details of construction may be had which will fall within the scope of the invention as claimed.

Having thus described my invention, what I claim as new is:

1. A window screen of the character described comprising a metallic frame formed of substantially flat elongated strips secured together at their opposite ends and having longitudinally extending substantially V-shaped intermediate projections formed

thereon, tongues struck out from the opposite sides of the V-shaped projections, a sheet of foraminous material disposed within the frame and having its marginal portions extending over the V-shaped projections, certain of said tongues penetrating the foraminous material and constituting means for anchoring same to the frame, and substantially V-shaped clamping strips mounted on the V-shaped projections in a manner to frictionally clamp the foraminous material therebetween, the tongue being bent over the opposite side portions of the clamping strips and constituting means for securing said strips on the frame.

2. A window screen of the character described comprising a metallic frame formed of elongated substantially flat side and end members rigidly connected together at their opposite ends longitudinally extending substantially V-shaped projection formed intermediate the longitudinal edges of each of the strips, a sheet of foraminous material disposed within the frame and having its marginal portions extending over the V-shaped projection, substantially V-shaped clamping strips mounted on the V-shaped projection in a manner to frictionally clamp the foraminous sheets therebetween, tongues struck out from the side and end members of the frame on opposite side of the V-shaped projection, certain of said tongues penetrating the foraminous sheet and constituting positive means for anchoring same to the frame, said tongues further being bent over the opposite side portions of the clamping strip and constituting means for securing said strips on the frame, an integral loop formed on the outer marginal edge of each of the side and end members and means for swingingly mounting the frame in a window frame comprising the hinge member mounted on said window frame and having a loop portion formed integral thereto and adapted to encircle the loop portion of one of the side members of the screen frame.

In testimony whereof I affix my signature.

ANDREW SONAFELT.
